UNITED STATES PATENT OFFICE

2,177,500

ELECTRIC VALVE CONVERTING SYSTEM

Hans Joachim Schmiedel, Berlin-Halensee, Germany, assignor to General Electric Company, a corporation of New York

Application March 4, 1938, Serial No. 194,007
In Germany March 6, 1937

10 Claims. (Cl. 175—363)

My invention relates to electric valve converting systems and more particularly to those systems in which an arc is periodically ignited and extinguished between a couple of electrodes and a continuous flow of some fluid medium is maintained between the electrodes.

Electric valves converting systems of the kind referred to have been described in a book by Erwin Marx entitled "Lichtbogenstromrichter" published in Berlin in 1932, and in United States Letters Patent No. 2,074,930 granted March 23, 1937, upon the application of Erwin Marx. In such stems it has been customary to provide a continuous flow of gas, such as air, within the gap between the electrodes. In some of the arrangements the principal pair of electrodes has been provided with an auxiliary electrode which served as a starting or ignition electrode. After an arc had been started between one of the principal electrodes and the auxiliary electrode the arc was carried over to the other principal electrode. Due to the action of the oxygen in the air the principal electrodes are subject to considerable deterioration and in accordance with my invention I propose to utilize a relatively inert gas. It also would be desirable upon termination of the normal conductance period, that is, at the time when the arc becomes extinguished, that some arrangement could be provided for the rapid deionization of the space between the principal electrodes. While the flow of any suitable fluid medium between electrodes will accomplish this result, in certain instances it may be desirable to shorten this period of deionization. Accordingly, in accordance with my invention I vary the flow of the fluid medium between the principal electrodes so that this fluid medium has an optimum flow at the time the arc is initiated and a relatively greater flow at the time that the arc is extinguished.

It is, therefore, an object of my invention to provide an improved electric valve converting system of the type referred to in which the flow of the fluid medium between the principal electrodes is controlled in accordance with the periodic initiation of an arc therebetween.

Still another object of my invention is to provide an improved electric valve converting system of the type referred to in which the direction of flow of a fluid medium passing between the principal electrodes reverses in accordance with the periods of conductivity and non-conductivity of the valve means.

Still another object of my invention is to provide an improved electric valve converting sys-

tem of the type referred to in which a fluid medium is circulated and recirculated through the valve means.

The novel features which I believe to be characteristic of my invention are set forth with particularity in the appended claims. My invention itself, however, both as to its organization and method of operation, together with further objects and advantages thereof, will be better understood by reference to the following description taken in connection with the accompanying drawings in which Fig. 1 shows one embodiment of my invention, and Figs. 2 and 3 show modifications of my invention.

Referring now to Fig. 1 of the drawings, I have illustrated therein an electric valve converting apparatus for transmitting energy between an alternating current circuit 10 and a direct current circuit 11. Since my invention is applicable to any of the electric valve converting systems well known in the art in which there is utilized an electric valve of the type referred to, the arrangement shown in Fig. 1 merely shows a half wave rectifying circuit for the purpose of simplicity in disclosure and explanation. The primary winding of a transformer 12 is energized from the alternating current source 10 and the secondary winding thereof is connected at one terminal to one side of the direct current circuit 11 and at the other terminal thereof to one of the principal electrodes of an electric valve 13 through a suitable inductor 14. The other side of the direct current 11 is connected through a similar inductor 15 to the other principal electrode of electric valve 13. Since the constructional details of the electric valve 13 do not form any part of my invention the representation in Fig. 1 is purely schematic. The electric valve 13 is provided with two principal electrodes 16 and 17 which are connected respectively to the inductors 14 and 15. As is well known by those skilled in the art of this type of electric valve means, some of these valves are only provided with two principal electrodes whereas others are provided with two principal electrodes together with an auxiliary or igniting electrode such as electrode 18, which is located in the proximity of the principal electrode 16. The auxiliary or starting electrode 18 is connected through two series capacitors 19 and 20 to one side of the direct current circuit 11. The capacitor 19 is bypassed by a suitable resistor 21 and the capacitor 20 is connected across one winding of a transformer 22 which is of the Tesla type. The primary winding of the Tesla transformer 22 is energized

through a rotary spark gap or commutator 23 which is interposed between the transformer 22 and the connections therefrom to the alternating current source 10. The rotary spark gap 23 or distributor is operated from a suitable motor 24 which is energized from the source of alternating current 10.

The operation of the valve system may be briefly described as follows: An alternating potential derived from the source 10 is impressed 10 between the principal electrodes 16 and 17 of the valve means 13 by means of a transformer 12. The auxiliary electrode 18 will have a potential substantially the same as the potential appearing 15 across the secondary winding of the Tesla transformer 22 since the capacitor 19 which is shunted by a resistor 21 is relatively small in value. The rotary spark gap 23 is synchronously driven by the motor 24. The moment of ignition 20 of the valves may be varied by adjusting the position of the commutator or rotary spark gap 23 thereby to control the power output of the electric valve converting system. When the rotary spark gap or commutator 23 energizes the Tesla 25 transformer, an oscillating circuit is formed by the capacitor 20 and one winding of the Tesla transformer so that a relatively high voltage is impressed upon the auxiliary electrode 18. As a result thereof an arc is initiated between the auxiliary electrode 18 and the main electrode 16. This initiation of an arc between the main and auxiliary electrodes causes an impulse to be impressed 30 across the main electrodes 16 and 17 so that an arc discharge is formed therebetween. Obviously, means should be provided for rapidly extinguishing the arc between the auxiliary electrode 18 and the main electrode 16 so that the main current will not flow through the auxiliary 35 spark gap. One means for preventing this is obtained by the use of a capacitor 19 and resistor 21.

The electric valve means 13 is so constructed as to receive a fluid medium such as a relatively inert gas, for example nitrogen, through suitable 40 duct openings 25 and 26 which are located at opposite ends of the surrounding casing or envelope of the electric valve means. The arrows indicate the direction of the flow of the medium through the end chambers into the main chamber 27. A portion of this medium also flows through the auxiliary chamber 28 so as to emerge between the principal electrode 16 and the auxiliary ignition electrode 18. The fluid medium then flows 45 through the openings in the principal electrodes past the reflectors 29 and 30, the smaller end chambers which are connected to the ducts 31 and 32. Ducts or conduits 25, 26, 31 and 32 are connected to a suitable source of fluid medium contained in the chambers 33 and 34. The chamber 33 is provided with a filter 35, a suitable cooling means 36 and an impeller fan 37 which is driven by a motor 38 energized from any suitable source of current 39. The chamber 34 is also provided with a suitable filter 40. The filters 50 35 and 40 serve to remove any impurities from the fluid medium and the cooling device 36 serves to reduce the temperature of the fluid medium to the proper value. In accordance with my invention, a valve 41 is connected on the intake 55 side of the valve means 13 so as to control the flow of the fluid medium in accordance with the initiation of the arc between the principal electrodes. The valve 41 is connected to be operated in synchronism with the rotary spark gap 60 or distributor 23 so that during the time for initia-

tion of the arc an optimum flow of the fluid medium will occur between the principal electrodes and at the end of the normal period of conductivity of the arc discharge between the electrodes the flow of the fluid medium will be increased so as to rapidly deionize the gap between the principal electrodes. It of course will be apparent to those skilled in the art that the valve means 41 may be constructed so as to properly control the flow of the fluid medium in accordance with the requirements of the operation of the electric valve means 13.

While the particular direction of flow of the fluid medium through the electric valve 13 has been indicated by arrows, it of course will be understood that my invention is not limited to the utilization of a device having this particular direction of flow and that any other device may be substituted having other orifices and arrangements for directing the flow of the fluid medium 15 between the principal electrodes of the valve means. In some arrangements, therefore, it may be desirable to periodically reverse the flow of the fluid medium between the principal electrodes in accordance with the periods of conductivity 20 and non-conductivity of the valve means. Such an arrangement has been shown in Fig. 2 in which the rectangle 13 represents the valve means of the same general type as that shown in Fig. 1. Two chambers 42 and 43 for containing a source 30 of fluid medium are provided, each of which is arranged to have a filter and cooling medium or device therein. The chambers 42 and 43 are connected respectively to the cylinders 44 and 45 which are each provided with suitable pistons 35 which are driven by the motor 24 which operates the synchronous rotary spark gap or distributor 23 which controls the ignition of the electric valve 13. Thus, during the period of conductivity of the valve 13 the fluid medium flows in one direction and during the period of non-conductivity 40 the fluid medium flows in the opposite direction.

A further modification of my invention is shown in Fig. 3 in which electric valve 13 is provided with two chambers 42 and 43, one of which is 45 connected to a cylinder 44 and the other of which is connected to a storage or compression tank 46. The cylinder 44 is operated from the synchronous motor 24 which drives the synchronous distributor or rotary spark gap 23. Thus, in this arrangement the flow of the fluid medium also periodically reverses in accordance with the periodic ignition of the arc between the principal electrodes of the valve means 13. In these arrangements the size of the chambers, the ducts and the 55 compression chamber may be so designed that the reversal of the flow of the fluid medium is amplified by a natural period of oscillation.

While I have shown a particular application of my invention to an electric valve converting apparatus, it is to be understood that this is merely illustrative as one of a number of electric valve converting or translating apparatus to which my invention may be applied. It will, of course, be understood that I do not wish to be limited thereto since it is apparent that the principles herein disclosed are susceptible of numerous other applications, and modifications may be made in the circuit arrangements and in the instrumentalities employed to which my invention may be applied 65 without departing from the spirit and scope of my invention as set forth in the appended claims.

What I claim as new and desire to secure by Letters Patent of the United States is:

1. In an electric valve converting system, the 75

5 combination comprising valve means including a pair of cold electrodes, means for periodically initiating an arc therebetween, a source of fluid medium, and means for controlling the flow of said medium through said valve means in synchronism with the periodic initiation of said arc.

10 2. In an electric valve converting system, the combination comprising valve means including a pair of cold electrodes within an envelope, means for periodically initiating an arc between said electrodes, a source of a relatively inert fluid medium, means for filtering said medium and means for controlling the flow of said medium through said valve means in synchronism with the periodic initiation of said arc.

15 3. In an electric valve converting system, the combination comprising valve means including a pair of cold electrodes within an envelope, means for periodically initiating an arc between said electrodes, a source of a relatively inert fluid medium, means for cooling said medium, and means for circulating and recirculating said medium through said envelope dependent upon the periodic initiation of said arc.

20 25 4. In an electric valve converting system, the combination comprising valve means including at least two cold electrodes, means for periodically initiating an arc therebetween, means for producing a flow of a fluid medium between said electrodes, and means for controlling the rate of flow of said medium in accordance with the periodic ignition of said arc.

25 30 35 5. In an electric valve converting system, the combination comprising valve means including a pair of cold electrodes, means for periodically initiating an arc between said electrodes, means for producing a flow of a fluid medium between said electrodes, and means for periodically reversing the direction of the flow of said medium in accordance with the periodic ignition of said arc.

40 45 6. In an electric valve converting system, the combination comprising valve means including a pair of cold electrodes, means for periodically initiating an arc therebetween, a source of fluid medium, means for circulating and recirculating

said medium through said valve means, and means for regulating the flow of said medium in accordance with the periodic initiation of said arc.

5 7. In an electric valve converting system, the combination comprising valve means including a pair of cold electrodes, means for periodically initiating an arc therebetween, a source of fluid medium, means for circulating and recirculating said medium through said valve means, and means for periodically reversing the direction of the flow of said medium in accordance with the periodic ignition of said arc.

10 15 8. In an electric valve converting system, the combination comprising valve means including a pair of cold electrodes, means for periodically initiating an arc between said electrodes, means for producing a flow of a fluid medium between said electrodes, means for periodically reversing the direction of the flow of said medium in accordance with the periodic ignition of said arc, and means for cooling and filtering said medium before it recirculates through said valve means.

20 25 9. In an electric valve converting system, the combination comprising valve means including a pair of cold electrodes, means for periodically initiating an arc therebetween, a source of fluid medium, means for circulating and recirculating said medium through said valve means, means for regulating the flow of said medium in accordance with the periodic initiation of said arc, and means for cooling and filtering said medium prior to recirculation of said medium through said valve means.

30 35 40 10. In an electric valve converting system, the combination comprising valve means including a pair of cold electrodes, means for periodically initiating an arc therebetween, a source of fluid medium, means for circulating and recirculating said medium through said valve means, means for periodically reversing the direction of the flow of said medium in accordance with the periodic ignition of said arc, and means for cooling and filtering said medium prior to recirculation thereof through said valve means.

45 HANS JOACHIM SCHMIEDEL.
